UNITED STATES PATENT OFFICE.

CHRISTEN J. PETERSON, OF CHICAGO, ILLINOIS.

MOTION-PICTURE MACHINE.

1,258,705.

Specification of Letters Patent. Patented Mar. 12, 1918.

Application filed May 2, 1917. Serial No. 166,013.

To all whom it may concern:

Be it known that I, CHRISTEN J. PETERSON, a citizen of the United States, residing at Chicago, in the county of Cook and State 5 of Illinois, have invented certain new and useful Improvements in Motion-Picture Machines, of which the following is a specification.

The present invention relates to the construction and arrangement of certain portions of the mechanism of a moving-picture machine to enable the intermittent film-actuating sprocket to be bodily shifted in order to move the film with respect to the light 10 aperture and frame the picture, and at the same time maintain the rest of the mechanism in proper position and timed relation.

One object of the invention is to arrange a driving gear connection between the intermittent film sprocket and its actuating 20 means and the means for rotating the shutter, which driving connection will at all times be maintained, thereby synchronizing the movements of the intermittent sprocket 25 and shutter.

Another object of the invention is to permit the sprocket to be bodily shifted for carrying out the framing operation, without changing or affecting in any way the 30 position of the shutter with respect to the light aperture.

A further object of the invention is to provide a shutter-carrying shaft and a shutter-actuating shaft with a telescoping or 35 slideable connection between these shafts, whereby one may be bodily moved without so moving the other.

A further object of the invention is to form the shutter-actuating shaft in two 40 parts, with a swivel or flexible connection between such parts.

A further object of the invention is to provide a carrier for the following parts: an intermittent film sprocket, its actuating 45 means, a gear connection from a main driving gear to said actuating means, a shutter-actuating shaft, and a gear connection between the main driving gear and shutter-actuating shaft, which carrier will be capable of movement as a unit about the center of rotation of the main driving gear.

A further object of the invention is to so arrange this carrier that when moved it will bodily move the intermittent film 55 sprocket in a direction longitudinally of the film, thereby effecting the necessary move-

ment of the film strip to carry out the framing operation.

The invention further consists in the features of construction and combination of 60 parts hereinafter described and claimed.

In the drawings:

Figure 1 is a side elevation of the machine of the present invention;

Fig. 2, a front view of said machine with 65 certain portions broken away;

Fig. 3, a vertical section showing the position of the parts prior to a framing operation;

Fig. 4, a view similar to Fig. 3, showing the position assumed by the parts after the framing operation has been made;

Fig. 5, a perspective of the carrying member, showing the gear connections mounted thereon;

Fig. 6, a diagrammatic view, showing the parts previous to a framing operation;

Fig. 7, a view similar to Fig. 6, showing the parts after the framing operation has been completed;

Fig. 8, a diagrammatic view of the gear connections;

Fig. 9, a sectional detail of the locking means for the carrier;

Fig. 10, a detail of the cam and star-wheel for imparting movement to the film-feeding sprocket; and

Fig. 11, a detail plan view of the gear connection to the shutter actuating shaft.

In the art to which the present invention 90 relates, owing to inaccuracies of one kind or another, the picture will get out of alignment with the light apertures, whereby part of one picture and part of another will be shown on the screen at the same time. This 95 is undesirable and must be corrected. Such correction is, so far as I am aware, generally made by rotating the intermittent sprocket at other than a normal movement, so as to move the film strip with other than 100 its normal movement; or to bodily shift the intermittent sprocket, which will produce a similar abnormal movement of the film strip. In either case the film strip is bodily moved otherwise than by the usual feeding movement to realine the picture with the light aperture. In so moving the intermittent sprocket, a synchronous driving connection between the said sprocket and shutter must be maintained. In the present invention, 105 by a simple means, this driving connection is properly maintained and the intermittent

110

sprocket is permitted to be bodily shifted, although no bodily shifting of the shutter takes place.

Referring to the drawings, the invention is illustrated in connection with the head 11 of a motion picture machine. This head carries the usual lens 12 and film gate 13, and is provided with light apertures 14, between which the film 15 passes. Mounted in the head is a main actuating shaft 16, revolved by means of a hand crank 17, or otherwise. On the end of the shaft 16 is a gear 18, meshing with a gear 19 on a stub shaft 20; and meshing with the gear 19, but 15 out of mesh with the gear 18, is a gear 21 on a shaft 22. This shaft 22 carries a film feed sprocket 23, actuated with a continuous movement and serving to draw the film off from the supply reel (not shown).

20 The gear 19 meshes with a pinion 24 of a shaft 25, which shaft carries a gear 26 medially thereof, and this shaft, on its end, carries a film take-up sprocket 27, which feeds the film toward the take-up reel (not 25 shown). Meshing with the gear 26 is a pinion 28 on a shaft 29, and on the end of this shaft is a cam member 30 equipped with a pin 31. This cam member lies within a casing 32, forming part of a carrying member 33, which latter will be more fully hereinafter described.

30 The cam 30 imparts an intermittent movement to a star-wheel 34 in the usual and well-known manner. This star-wheel is mounted on a shaft 35, which carries the intermittent film sprocket 36, and thus the sprocket is operated intermittently by the intermittent movements of the star-wheel. The star-wheel 34 is located within the casing 32, 40 while the sprocket 36 is outside of this casing, as will be apparent from the drawings. Suitable presser rolls 37 are provided for the sprockets 23, 27 and 36 to maintain the film strip against the peripheries of said sprockets.

45 Meshing with the gear 26 is a pinion 38 on a stub shaft 39. This stub shaft is mounted in the upper end 40 of the carrier 33 and, as will be seen from the drawing, 50 the pinion 38 is arranged at approximately right angles to the pinion 28 as respects radial lines from the centers of said pinions to the center of the gear 26.

55 Mounted on the stub shaft 39 is a bevel gear 41 meshing with a bevel gear 42^a, which is secured to a shaft section 42, forming part of the shutter-actuating shaft. The other portion of the shaft consists of the section 43; and said sections are coupled together 60 by means of a swivel coupling 44. This method of connecting causes the two shaft sections to rotate together, but enables the section 42 to assume a position out of parallelism with respect to the section 43 when 65 the carrier 33 is moved in performing the

framing operation. A bracket 45 is pivotally connected to the upper end 40 of the carrier 33 and embraces the shaft section 42 (sec Fig. 11). The pivotal center of the bracket is the stub shaft 39. This allows the bevel gear 42^a to remain in mesh with the bevel gear 41 as the parts are turned in the framing operation, and at the same time no great degree of angularity is imparted to the shaft section 42.

75 The shutter 46 is mounted on a shutter-carrying shaft 47, which is held by a fixed mounting 48. The shaft 47 as shown is hollow, and within said shaft extends the shaft section 43. There is a spline connection between this shaft section and the shaft 47, whereby these two parts are rotatably driven in unison, but one may slide or telescope with respect to the other.

80 As stated, the carrier 33 is mounted to swing about the center of the shaft 25, which carries the main actuating gear 26. The carrier is formed with a horizontal bore 49, within which is a sleeve 50 secured to a fixed part of the frame of the machine. 90 The shaft 25 extends through this sleeve with a free turning fit. The carrier turns on the periphery of the sleeve 50, but since this sleeve is concentric with the shaft 25, the movement of the carrier is about the 95 center of the said shaft.

95 The carrier is formed with a bore 51 (see Fig. 9), in which is positioned a block 52, having a cam or wedge face 53, which bears against the periphery of the sleeve 49. Extending through this block is the reduced end 54 of a combined actuating and locking rod 55; and the lower portion 56 of said reduced end of such rod is entered into a tapped recess 57 in the carrier. By turning 100 the rod 55, the shoulder 58 thereon will be brought into engagement with the block and the block thereby forced downward, which will bring the cam surface 53 into hard engagement with the sleeve 50, and the carrying member is thus locked against turning movement. By turning the rod in the opposite direction, pressure from the block will be relieved and the carrier be free to turn. In the turning movement, the rod 55 will 105 be used as a lever. Thus, such rod constitutes a combined means for controlling the locking of the carrier against a turning movement, and for obtaining a leverage to turn the carrier.

110 The action of the parts during a framing movement will be best understood from Figs. 3, 4, 6 and 7. In Figs. 6 and 7, marks 59 have been placed on the film strip 15 to indicate the division line between pictures. 115 Referring to Fig. 6, as there shown the film strip has gotten into a position, by reason of inaccuracies, wherein half of one picture and half of another are being projected upon the screen at the same time, and under such 120

conditions it is desired to shift the film strip to realine the pictures with the light aperture.

In performing this framing operation, the 5 rod 55 is rotated to loosen the block 52 from the sleeve 50, and pressure is then placed upon the rod to swing the carrier member. As shown in the drawings, the carrier member is swung in a direction to carry the intermittent sprocket 36 downward, although the same result could be obtained by so swinging the carrier as to move the intermittent sprocket upward. When swung, as shown, the intermittent sprocket, star and 10 cam wheel will be bodily and simultaneously moved from the position of Fig. 3 to the position of Fig. 4, and, as will be understood from Figs. 6 and 7, such movement carries the film sprocket downward in a direction longitudinally of the film strip. When so moved, the sprocket will pull the film strip downward and aline the pictures with the light aperture, as will be understood from Fig. 7. The direction of movement of the intermittent sprocket being longitudinally of the film, will be in the direction best suited to cause a movement of the film simultaneously with the movement of the intermittent sprocket. 15

It is to be remembered that the intermittent film sprocket, star-wheel, and cam disk all move bodily and in unison, and the relative position between the centers of movement of these parts is never changed; and, 20 further, by reason of the carrier swinging about the center of the shaft 25, the pinion 28 will travel about the periphery of the gear 26 and will always remain in mesh therewith, whereby a constant driving connection to the cam disk will always be maintained. 25

When the carrier 33 is swung as above described, the upper end 40 thereof will be moved toward the film strip, as will be understood from a comparison of Figs. 6 and 45 7. This carries the gears 38, 41, and 42^a in a similar direction. Such movement being around the center of the main actuating gear 26, the pinion 38 will travel around the 50 periphery of the gear 26 and remain in mesh therewith at all times. This causes a driving connection to the shutter-actuating shaft 42 to be maintained at all times, and also maintains a continuous driving connection 55 between the cam and shutter, so that the timed relation between the intermittent sprocket and shutter is never disturbed.

When the above described movement takes place, the sections 42 and 43 of the shutter- 60 actuating shaft will be pulled toward the film shutter, but owing to the spline connection between the section 42 and the shutter-carrying shaft 47, such movement will not be communicated to the shaft 47, and it will 65 remain stationary, as respects all other move-

ments save a rotative one about its axis. When the carrier 33 is turned to perform the framing operation, there may be some abnormal movement of the gears 38 and 28 as they travel about the periphery of the gear 26. Such movement either accelerates or retards the normal movement of the gears 38 and 28. This abnormal movement will be transmitted to the cam and to the shutter, but since it will be imparted to both in a like degree and simultaneously, no improper timing of the cam or shutter will take place. The shutter carrying shaft having no movement, save a rotative one about its axis, the shutter will remain at all times the same distance away from the light aperture. 75

The movement of the carrier, being about the center of the shaft 25, is an arcuate one, and hence the gears 38, 41 and 42^a will travel in an arcuate path. The movement of the 85 shutter-actuating shaft with respect to the shutter-carrying shaft must be, with the construction shown, a straight line movement, and therefore I interpose the flexible joint 44 between the shaft sections 42 and 43 and 90 a pivotal connection between the bracket 45 and the carrying member, allowing the gear 42^a to follow in the arcuate path of movement of the gears 38 and 41. The pivotal connection above referred to allows the gears 95 41 and 42^a to remain constantly in mesh and at the same time places the shaft section 42 but slightly at an angle to the shaft section 43, thus maintaining an efficient driving connection to the shutter. It also allows the 100 shaft section 43 to have a straight line movement and therefore to readily and easily move in and out with respect to the shutter-carrying shaft 47.

From the foregoing it is apparent that by 105 a simple and durable means, I am enabled to bodily move the intermittent film sprocket to effect a movement of the film strip and frame the picture. At the same time, the relative positions of the axial centers of the 110 intermittent sprocket, cam and star wheel are not changed, so that no disruption of the movements of these parts takes place. The shutter remains at all times a fixed distance from the light aperture, and the driving connection between the intermittent sprocket and shutter is maintained at all times, so that the proper timing is maintained between 115 these parts.

I claim:

1. In a motion picture machine, the combination of film advancing means, means for actuating said advancing means, a shutter, a shutter-operating shaft, a shutter-carrying shaft held against movement other than a 125 rotative one about its own axis, a main actuating gear, a gear connection from said main actuating gear to said film advancing actuating means, a gear connection from said main actuating gear to said shutter- 130

- operating shaft, a carrying member for said film advancing means, film advancing actuating means, shutter-operating shaft, and said gear connections, said carrying member 5 being arranged to move about the center of the main actuating gear, and a slidable driving connection between the shutter-operating and carrying shafts, substantially as described.
- 10 2. In a motion picture machine, the combination of film advancing means, means for actuating said advancing means, a shutter-carrying shaft held against movement other than a rotative one about its axis, a shutter- 70 actuating shaft, a slidable driving connection between said shafts, means for bodily and simultaneously shifting said film advancing means, its actuating means, the shutter-actuating shaft and its operating 75 means, to frame the picture, and means for maintaining a constant driving connection between the film advancing actuating means and shutter-operating shaft, substantially as described.
- 15 3. In a motion picture machine, the combination of film advancing means, means for actuating the same, a shutter, a shutter carrying shaft held against movement other than a rotative one about its axis, shiftable 80 driving means for said shutter carrying shaft, means for simultaneously shifting the film advancing means, actuating means therefor, and shutter shaft driving means bodily to effect a framing operation, a connection 85 between the shutter shaft driving means and shutter shaft permitting the driving means to shift bodily without so shifting said shaft, whereby the shutter is maintained 90 at all times the same distance from the light 95 aperture, and whereby a driving connection between the film advancing actuating means and shutter shaft driving means is provided which remains in operative engagement at 100 all times, substantially as described.
- 40 4. In a motion picture machine, the combination of film advancing means, means for actuating said advancing means, a shutter, a shutter-operating shaft, a shutter-carrying shaft held against movement other than a 105 rotative one about its axis, a slidable driving connection between said shafts, a main driving member, a connection between the main driving member and film advancing 110 actuating means, a connection between the main driving member and shutter-operating shaft, means for simultaneously and bodily moving said film advancing means, actuating means therefor, shutter-actuating shaft and outer gears of the planetary gear about the 115 axis of the central gear thereof, and a slid- 120 able driving connection between the shutter-actuating shaft and shutter-carrying means, substantially as described.
- 45 5. In a motion picture machine, the combination of film advancing means, means for actuating said advancing means, a shutter-carrying shaft held against movement other than a rotative one about its axis, a shutter- 125 actuating shaft, a slidable driving connection between said shafts, means for bodily and simultaneously shifting said film advancing means, the actuating means therefor and, the shutter-actuating shaft, to 130 frame the picture, means for maintaining a constant driving connection between the film advancing actuating means and shutter-actuating shaft, and means for locking said shiftable parts against such shiftable movement, substantially as described.

6. In a motion picture machine, the combination of film advancing means, means for actuating said film advancing means, a shutter, a shutter-operating shaft, a shutter-carrying shaft held against movement other than a rotative one about its axis, a slidable driving connection between said shafts, a main driving member, a connection between the main driving member and film advancing 90 actuating means, a connection between the main driving member and shutter-operating shaft, means for simultaneously and bodily moving said film advancing means, its actuating means, shutter-operating shaft 95 and connections from the main driving gear about said main driving member as a center to frame the picture, whereby a continuous driving connection between the film advancing actuating means and shutter shaft 100 is maintained, and means for locking said movable parts against movement, substantially as described.

7. In a motion picture machine, a framing device comprising film advancing means, actuating means therefor, a shutter, a shutter-actuating shaft, shutter-carrying means held against movement other than a rotative one about its axis, a planetary gear drive for the film advancing means and shutter-actuating 105 shaft, means for simultaneously and bodily moving the film advancing means, actuating means therefor, shutter-actuating shaft and outer gears of the planetary gear about the 110 axis of the central gear thereof, and a slid- 115 able driving connection between the shutter-actuating shaft and shutter-carrying means, substantially as described.

8. In a motion picture machine, a framing device comprising film advancing means, actuating means therefor, a shutter, a shutter-actuating shaft, shutter-carrying means held against movement other than a rotative one about its axis, a planetary gear drive for the film advancing actuating means and shutter-actuating shaft, means for simultaneously and bodily moving the film advancing means, actuating means therefor, shutter-actuating shaft and outer gears of the planetary gear about the 120 125 130 axis of the central gear thereof, and a slid- able driving connection between the shutter-actuating shaft and shutter-carrying means, substantially as described.

axis of the central gear thereof, a slidable driving connection between the shutter-actuating shaft and shutter-carrying means, and means for locking such movable parts 5 against movement, substantially as described.

9. In a motion picture machine, the combination of a head comprising a fixed portion and a movable portion, said movable 10 portion consisting of an angled member, film advancing means, and means for actuating the same carried by one arm of the sprocket, a shutter, a shutter-operating shaft carried by the other arm, said angled member 15 when moved to frame the picture carrying simultaneously and bodily the film advancing means and actuating means therefor in one direction and the shutter-operating shaft in a direction at an angle there- 20 to, a shutter mounting held against movement other than a rotative one about its axis, a slidable driving connection between the shutter-actuating shaft and shutter mounting, and means for maintaining a constant 25 driving connection between the film advancing actuating means and shutter-operating shaft, substantially as described.

10. A framing device for a motion picture machine, comprising a carrying means 30 adapted to move as a unit, film advancing means and actuating means therefor on said carrying means, a shutter, a shutter-operating shaft formed of two sections connected by a flexible joint, a connection between 35 one of said sections and the carrying means, a shutter mounting held against movement other than a rotative one about its axis, a shiftable connection between the other section and the shutter mounting, and means 40 for maintaining a constant driving connection between the shutter-operating shaft and film advancing actuating means, substan- tially as described.

11. In a motion picture machine, the combination of film advancing means, means for 45 actuating the same, a shutter-operating shaft, formed in two sections connected by a flexible joint, a shutter-carrying member held against movement other than a rotative 50 one about its axis, a spline connection be- 55 between one of said sections and said shutter- carrying member, means for simultaneously and bodily moving said shaft sections, film advancing means and actuating means there- 60 for to frame the picture, and means for maintaining a constant driving connection between said film advancing actuating means and said shutter-operating shaft, substan- tially as described.

60 12. In a motion picture machine, the combination of film advancing means, means for actuating the same, a shutter, a shutter-operating shaft, a shutter mounting held against movement other than a rotative one 65 about its axis, a telescopic drive connection

between the shutter-operating shaft and shutter mounting, means for bodily and simultaneously shifting the said film advancing means, said actuating means therefor and shutter-operating shaft to frame the 70 picture, and means for maintaining a constant drive connection between the film advancing actuating means and shutter-operating shaft, substantially as described.

13. In a motion picture machine, the combination of film advancing means, means 75 for actuating the same, a shutter, a shutter-operating shaft, a shutter mounting held against movement other than a rotative one about its axis, a slidable driving connection 80 between the shutter-operating shaft and the shutter mounting, means for bodily and simultaneously shifting said film advancing means, actuating means therefor and shutter-operating shaft to frame the picture, and 85 means for maintaining a constant driving connection between the film advancing actuating means and shutter-operating shaft, substantially as described.

14. In a motion picture machine, the combination of film advancing means, means for 90 actuating the same, a shutter, a shutter-operating shaft, a shutter mounting held against movement other than a rotative one about its axis, means permitting a slidable 95 and pivotal movement of said shutter-operating shaft with respect to said shutter mounting, means for maintaining a driving connection between said shaft and mounting, means for simultaneously and 100 bodily shifting said film advancing means, actuating means therefor and shutter-operating shaft to frame the picture, and means for maintaining a constant driving connection between said film advancing actuating 105 means and shutter-operating shaft, substantially as described.

15. In a motion picture machine, the combination of film advancing means, means for 110 actuating the same, a shutter, a shutter-operating shaft, a shutter mounting held against movement other than a rotative one about its axial center, a slidable and pivotal driving connection between the shutter-operating shaft and shutter mounting, means 115 for simultaneously imparting a bodily arcuate movement about a common center to the film advancing means, the actuating means therefor and shutter-operating shaft to frame the picture, and means for main- 120 taining a constant driving connection be- 125 tween the film advancing actuating means and shutter-operating shaft, substantially as described.

16. In a motion picture machine, the combination of film advancing means, means for 130 actuating the same, a shutter, a shutter-operating shaft, a shutter mounting held against movement other than a pivotal one about its axis, a slidable and pivotal driving connec-

tion between the shutter-operating shaft and shutter mounting, a common driving member for the film advancing actuating means and shutter-operating shaft, a mounting for the film advancing means, its actuating means and shutter-operating shaft permitting them to swing bodily and simultaneously about the center of rotation of the common driving member to frame the picture, and means for maintaining during such movement a constant driving connection between the film advancing actuating means and shutter-operating shaft, substantially as described.

17. In a motion picture machine, the combination of film advancing means, actuating means therefor, a shutter, a shutter-operating shaft held against movement other

than a rotative one about its axis, a main actuating gear, a gear connection from said main actuating gear to said film advancing actuating means, a gear connection from said main actuating gear to said shutter-operating shaft embodying a gear on said operating shaft, a carrying member for said film advancing means, the actuating means therefor, shutter-operating shaft and said gear connections, a pivotal connection between the shutter-operating shaft and carrying member, said carrying member being arranged to move about the center of the main actuating gear, and a slidable driving connection between the shutter-operating and carrying shafts, substantially as described.

CHRISTEN J. PETERSON.
